COMBINATION DISPLAY PACKAGE FOR TABLE LEGS AND APPURTEnant HARDWARE OR THE LIKE

Glenn I. Barton, Seattle, Wash., assignor to Totem Wood Industries, Seattle, Wash., a corporation of Washington

Application December 23, 1957, Serial No. 48,994

Term of patent 14 years

(Cl. D80—5)

Figure 1 is a perspective view of a combination display package for table legs and appurtenant hardware or the like, showing my new design;

Figure 2 is a top plan view thereof; and

Figure 3 is a transverse medial cross-sectional view taken on line 3—3 of Figure 1, looking in the direction of the arrows.

The rear of the package is substantially plain.

I claim:

The ornamental design for a combination display package for table legs and appurtenant hardware or the like, as shown and described.
